METHOD AND APPARATUS FOR MAKING
HOOD CAPSKenneth R. Allen, Ridgewood, N. Y., assignor to
American Seal-Kap Corporation of Delaware,
Wilmington, Del., a corporation of Delaware

Application November 24, 1942, Serial No. 486,730

6 Claims. (Cl. 93—60)

This invention relates to hood caps for milk bottles or the like and more particularly to a hood cap having a pleated skirt extending around the outside of the bottle neck and having its folds adhesively secured together.

An object of the invention is to provide a cap of the above type having novel and improved characteristics.

Another object is to provide a cap of the above type having pleats which are folded to effect a maximum sealing area.

Another object is to provide a novel and improved method and apparatus for forming a cap of the above type.

Various other objects and advantages will be apparent as the nature of the invention is more fully disclosed.

Although the novel features which are believed to be characteristic of this invention are pointed out more particularly in the claims appended hereto, the invention itself may be better understood by referring to the following description, taken in connection with the accompanying drawings in which a specific embodiment thereof has been set forth for purposes of illustration.

In the drawings,

Fig. 1 is a vertical section through the upper die embodying the present invention;

Fig. 2 is a vertical section through the lower die embodying the present invention;

Fig. 3 is a vertical section through the upper and lower dies in final cap-forming position;

Figs. 4, 5, 6 and 7 are fragmentary detail views showing successive positions of the die members;

Fig. 8 is a section taken on the line 8—8 of Fig. 7 showing the shape of the pleated skirt;

Fig. 9 is a perspective view of the pressure ring;

Fig. 10 is a perspective view of the draw plate body;

Fig. 11 is a perspective view of the upper forming ring;

Fig. 12 is a perspective view of the lower forming ring;

Fig. 13 is a top plan view of the formed cap;

Fig. 14 is a side elevation thereof;

Fig. 15 is a side elevation of the cap as applied to a bottle; and

Fig. 16 is an enlarged developed detail view showing the pleat folds.

In the following description certain specific terms are used for convenience in referring to various details of the invention. It is to be understood, however, that these terms are to be

given as broad an interpretation as the state of the art will permit.

A tamper-proof, hood cap for milk bottles, in accordance with the present invention, is shown in Figs. 13, 14, 15 and 16. This cap comprises a central diaphragm 10, a pouring lip housing 11 having a vertical inner wall 12, a top 13 and a plurality of raised ribs or top corrugations 14 and a folded or pleated skirt 15, which extends outwardly from the pouring lip housing 13. The skirt 15 is creased along fold lines 16, 17 and 18 to form flat sections 19 and inclined sections 20 and 21, which are adapted to be folded over

around the neck 22 of a milk bottle as shown in Fig. 15. The folds are held in position around the bottle neck by a suitable adhesive which is applied to the outside surface of the skirt. The adhesive is preferably made in the form of a narrow band 23 around the lower edge of the outside

20 of the skirt, although the width of the band may be varied as desired, or the adhesive may be applied to the entire outer surface of the skirt depending upon the required characteristics of the cap. The adhesive is applied to the outer sur-

25 face of the skirt rather than the inner surface inasmuch as this prevents contamination of the bottle and simplifies the cleaning problem. The cap may be made from a paper blank or from a thin flexible metal such as aluminum foil or other flexible material.

A feature of the present invention resides in arranging the folds so that the entire width of the band 23 is available for sealing purposes.

In order to accomplish this, the fold lines 16, 17 and 18 are so arranged that when the skirt is folded over around the neck of a bottle, as shown in Figs. 15 and 16, with the sections 20 and 21 inturned to form a concealed pleat 25, the lower edge 24 of the section 21 comes into exact regis-

20 tration with the lower edge of the underlying section 20, with the corresponding portions of the band 23 of the contacting surfaces also in regis-

25 tration.

The concealed fold line or crease 18 extends rearwardly at an angle to the vertical and the bottom edge 24 of the concealed pleat 25 is dis-

30 placed upwardly as shown in Fig. 16. However, this does not reduce the area of contact of the adhesive surfaces inasmuch as the folded-over portion of the adhesive band in the concealed pleat 25 registers with the underlying portion of the adhesive band on the outer face of the under

layer. Under these conditions it is found that the fold line 17 defining the edge of the outer fold, extends substantially vertically when the

35

40

45

50

55

skirt is folded around the outside of the bottle neck, as shown in Fig. 15.

In addition to providing a maximum sealing area, the cap thus formed has a neat and pleasing appearance inasmuch as the lower edge is substantially uniform around the entire skirt. In fact, the lower edge comprises a series of arcs corresponding in radius to the original blank, although the appearance to the eye approximates a straight line. Hence, the cap may be considered when in place to have a substantially straight, lower edge.

The die for forming this cap is shown in Figs. 1 to 12. Referring first to Fig. 1, the upper die is shown as comprising a support 30 to which a drawplate sleeve holder 31 and an upper forming ring 32 are secured by means of a retaining ring 33. A drawplate sleeve 34 as shown in Fig. 10, having a plurality of outwardly extending fins 35, is positioned within the sleeve holder 31 and may be secured thereto by suitable means, shown as a set screw 36. The fins 35 register with the corrugations 14 of the caps and are adapted to press out and form such corrugations.

A pressure ring 40, which is shown in detail in Fig. 9 as comprising a body 41 and a downwardly extending flange 42 provided with vertical slits 43, is mounted for vertical sliding movement around the outside of the drawplate sleeve 34 with the slots 43 in registration with and sliding over the fins 35 of the drawplate sleeve. The pressure ring 40 is held downwardly by a plurality of springs 44 which are mounted in spring sleeves 45 and are carried on pins 46 which are secured in the support 30. The upper surface 47 of the pressure ring 40 is adapted to engage against the lower surface of a lip 48 on the sleeve holder 31 for limiting the upward movement of the pressure ring.

The upper forming ring 32, as shown in detail in Fig. 11, is provided with a top flange 50 which engages the retaining ring 33 for securing the forming ring in place. The lower surface of the forming ring 32 is provided with flat, triangular sections 51 and inclined sections 52 and 53 conforming to the flat section 19 and the inclined sections 20 and 21 respectively of the top of the cap skirt.

A drawplate 60 having a flat lower surface 61 conforming to the diaphragm 18 of the cap and a vertical peripheral surface 62 conforming to the vertical surface 12 of the pouring lip housing, is secured to a drawplate cap 63. The drawplate cap 63 is provided with a flange 64 which bears against a shoulder 65 on the inner surface of the cylindrical drawplate sleeve 34 for limiting the movement thereof. A coiled spring 66, mounted in a recess 67 in the support 30, bears against the shoulder 64 for holding the drawplate 60 in its lower position. The drawplate cap 63 carries a spring 71 bearing against a flange 70 on an ejector pin 72 which extends through the bottom of the drawplate 60 for ejecting the cap. The flange 70 also limits the outward movement of the ejector pin 72. The forming ring 32 and the sleeve holder 31 are held in proper alignment by means of an aligning key 78.

It is to be noted that in the above construction the forming ring 32 and the drawplate sleeve 34, including the fins 35, are rigid with the support 30. The drawplate 60 is spring mounted for limited movement by means of the spring 66. The pressure ring 40 is likewise spring mounted by means of the springs 44 which are compara-

tively light with respect to the spring 66. The spring 71, carrying the ejector pin, is a light spring inasmuch as its only purpose is to eject the formed cap from the die.

Referring now to Fig. 2, the lower die comprises a support 80 carrying a draw ring 81, a lower forming ring 82, and a spring mounted draw block 83. The draw ring 81 conforms to the inner surface of the pouring lip housing 11 of the cap and is provided with a flange 84 which is engaged by a shoulder 85 on a retaining ring 86 to secure the same to the support 80.

The lower forming ring 82 is spring mounted by means of a spring 87 carried in sleeves 88 secured in the under surface of the forming ring 82. The lower forming ring 82, as shown in detail in Fig. 12, comprises flat sections 89 and inclined sections 90 and 92 conforming to the undersurface of the sections 19, 21 and 20 respectively of the cap skirt. The movement of the forming ring 82 is limited by the flange 84 of the draw ring and a shoulder 85 on the retaining ring 86.

The draw block 83 is in the form of a hollow cup in which a spring 93 is seated and is formed with a shoulder 94 bearing against a cooperating shoulder on the draw ring 81 for limiting the movement of the draw block. The various elements are held in proper alignment by means of an aligning key 95. The retaining ring 86 is provided with a conical top surface 96 which is arranged so as not to interfere with the blank 100 during the forming operation.

At the beginning of the forming operation the upper and lower dies are in the position shown in Figs. 1 and 2. The draw block 83 and the lower forming ring 82 are held in their upper position with their top surfaces in the same plane as the top surface of the draw ring 81 to receive a flat blank 100. In the upper die the drawplate 60 and the pressure ring 40 are held in their lower position by the springs 66 and 44 respectively. As the dies are brought together for forming the cap, they take the successive positions shown in Figs. 4, 5, 6, 7 and 3 respectively. In the first position, as shown in Fig. 4, the ejector pin 72 engages the blank 100 and is retracted against the pressure of the spring 71 to permit the drawplate 60 to engage the portion of the blank 100 which is on the draw block 83.

On further downward movement of the upper die, the drawplate 60 depresses the draw block 83, thus cupping the blank to form the diaphragm 18 and the inner walls 12 of the pouring lip housing as shown in Figs. 5, 6 and 7. During this part of the drawing operation, the outer diameter of the blank is reduced as the blank is drawn inwardly due to the cupping operation. The pressure ring 40 rests lightly upon the pouring lip housing of the blank on the draw ring 81 and the skirt portion of the cap is loosely held between the upper forming ring 32 and the lower forming ring 82.

In the positions shown in Figs. 5, 6 and 7, the pressure ring 40 maintains flat the portion of the blank extending across the draw ring 81, but permits the surplus blank material to be drawn into the slots 43, thereby definitely locating the folds. After the blank has been completely drawn and the dies are brought into their final position, as shown in Fig. 3, the fins 35 of the drawplate sleeve 34 strike against the upper surface of the gathered material within the slots 43 to smooth out and form the corrugations 14 on the pouring lip housing. At the same time, the pressure ring 40 is brought up against the flange 48 of

the sleeve holder 34 and the lower forming ring 82 engages the flange 84 which rigidifies the entire die assembly. The upper and lower forming rings thus strike to form the folds 16, 17 and 18 in the skirt of the cap while the pressure ring 48 strikes against the top of the pouring lip housing on the draw ring 84 for smoothing and forming the same.

It is to be noted that in this operation the blank is first drawn inwardly as it is cupped and the folds are initiated in the free space provided by the slots 43 of the pressure ring. The folds are thus guided as they are formed so that the natural crease in the paper is used for forming the corrugations 14 as well as for forming the actual folds of the skirt cap.

The springs 86 and 88 permit adjustment for variations in depth of the pouring lip housing. Shims of varying thickness may be placed beneath the draw block 83 so as to limit the downward movement thereof. The spring 86 is sufficiently rigid to permit the drawplate 60 to accommodate various positions of the draw block while retaining the necessary pressure in the cap diaphragm.

The inner surface of the draw ring may be provided with a plurality of raised ribs 120 for the purpose of forming vent grooves 121 in the outer surface of the wall 12 of the cap. These ribs 120 may extend over the top of the draw ring, as indicated at 122, to form bosses registering with the fins 38 of the drawplate sleeve which assist in forming and compressing the corrugations 14 on the pouring lip housing.

As will be noted from the above description, a feature of the present die resides in the provision of means, such as the grooves 43 in the pressure ring to guide and locate the folds of the paper which are produced as the paper is drawn inwardly due to the cupping operation. The extra thickness of paper thus produced in the pouring lip housing is formed into the corrugation 14 and the folds in the skirt are shaped by drawing between the upper and lower forming rings and by the subsequent application of pressure thereto by the striking of the upper and lower forming rings at the end of the operation.

The cap may include an inner disc, not shown, which may be seated within the cup formed by the diaphragm 10 and the walls 12 and may assist in holding the cap in position on the bottle. Such disc may also be used to carry the necessary printing for identifying the contents of the bottle.

Although a specific embodiment of the invention has been set forth for purposes of illustration, it is to be understood that various changes and modifications may be made therein and that the invention is capable of various uses as will be apparent to a person skilled in the art.

What is claimed is:

1. The method of forming a milk bottle cap or the like having a central depressed diaphragm, a pouring lip housing and an outwardly extending skirt from a blank, which comprises first cupping said blank to form said central depressed diaphragm while drawing the portions to form the skirt and pouring lip housing inwardly as the cupping progresses to form radial folds therein, confining the folds as the blank is drawn inwardly to definite locations around the periphery of said pouring lip housing portion, forming the pouring lip housing, pressing the folded material to form corrugations on the top of said pouring lip hous-

ing, and shaping the folds in said skirt portion to form said skirt.

2. A die for making a milk bottle cap or the like having a central depressed diaphragm, a pouring lip housing and an outwardly extending skirt, said die comprising members for cupping the central portion of a blank for forming said depressed diaphragm portion and drawing the outer portions of the blank inwardly as the cupping progresses to form radial folds thereon, members for confining the location of the folds as the blank is drawn inwardly during the cupping operation to definite locations around the periphery of the pouring lip housing portion, members for die-forming the folded material on the upper surface of the pouring lip housing portion to form a pouring lip housing having ribs, members for die-forming fold lines in the skirt portion to form the skirt, and means actuating said members in the order named.

3. A die for forming a hood milk bottle cap or the like having a central depressed diaphragm, a pouring lip housing and an outwardly extending skirt, said die comprising upper and lower die members having a drawplate and a draw block respectively conforming to said depressed diaphragm, and a pressure ring and a draw ring respectively conforming to the pouring lip housing, means moving said drawplate and draw block downwardly with respect to said draw ring for cupping the blank to form said central depressed diaphragm, means holding said pressure ring in loose pressure engagement with said draw ring during the cupping operation, said pressure ring having a plurality of spaced slots therein to receive and locate the folds of the blank material as the skirt portion is drawn inwardly during the cupping operation, a plurality of fins slidably disposed in said slots and means bringing said fins into pressure engagement with the material in said slots for compacting the same to form ribs on said pouring lip housing.

4. A die for forming a hood milk bottle cap or the like having a central depressed diaphragm, a pouring lip housing and an outwardly extending skirt, said die comprising upper and lower die members having a drawplate and a draw block respectively conforming to said depressed diaphragm, and a pressure ring and a draw ring respectively conforming to the pouring lip housing, means moving said drawplate and draw block downwardly with respect to said draw ring for cupping the blank to form said central depressed diaphragm, means holding said pressure ring in loose pressure engagement with said draw ring during the cupping operation, said pressure ring having a plurality of spaced slots therein to receive and locate the folds of the blank material as the skirt portion is drawn inwardly during the cupping operation, a plurality of fins slidably disposed in said slots and means bringing said fins into pressure engagement with the material in said slots for compacting the same to form ribs on said pouring lip housing, and means bringing said pressure ring into pressure engagement with the material on said draw ring for pressing and forming said pouring lip housing.

5. A die for forming a hood milk bottle cap or the like having a central depressed diaphragm, a pouring lip housing and an outwardly extending skirt, said die comprising upper and lower die members having a drawplate and a draw block respectively conforming to said depressed diaphragm, and a pressure ring and a draw ring re-

spectively conforming to the pouring lip housing, means moving said drawplate and draw block downwardly with respect to said draw ring for cupping the blank to form said central depressed diaphragm, means holding said pressure ring in loose pressure engagement with said draw ring during the cupping operation, said pressure ring having a plurality of spaced slots therein to receive and locate the folds of the blank material as the skirt portion is drawn inwardly during the cupping operation, a plurality of fins slidably disposed in said slots, means bringing said fins into pressure engagement with the material in said slots for compacting the same to form ribs on said pouring lip housing, and means bringing said pressure ring into pressure engagement with the material on said draw ring for pressing and forming said pouring lip housing, upper and lower forming rings carried by said upper and lower die members respectively, one of said forming rings being resiliently mounted for limited movement for guiding the folds as the blank is drawn inwardly during the cupping operation and means bringing said forming rings into pressure engagement with the skirt portion for forming the crease folds in said skirt.

6. A die for forming a milk bottle cap having

5 a central depressed diaphragm, a pouring lip housing, and an outwardly extending skirt, said die comprising a support, a forming ring conforming to the shape of the cap skirt rigidly secured to said support, a drawplate conforming to said central depressed diaphragm, spring means securing said drawplate to said support for relative vertical movement, a pressure ring disposed between said drawplate and said forming ring and 10 conforming to the top of said pouring lip housing, resilient means mounted on said pressure ring for limited vertical movement, a plurality of vertical slots in said pressure ring adapted to permit the blank material to be drawn therethrough as the blank is cupped, a sleeve rigidly secured in said support and having fins extending through said slots, and means responsive to downward movement of said support to first depress said draw plate to cup said blank and form said depressed diaphragm portion of the cap while holding said pressure ring under light pressure on said pouring lip housing with said fins in elevated position, and then to hold said pressure ring, fins and forming ring rigid with said support to apply high 15 20 25 forming pressure to said pouring lip housing and skirt.

KENNETH R. ALLEN.
